UNITED STATES PATENT OFFICE.

WILLIAM C. STEWART, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON SOLES.

1,271,795.

Specification of Letters Patent.

Patented July 9, 1918.

Application filed April 12, 1916. Serial No. 90,572.

To all whom it may concern:

Be it known that I, WILLIAM C. STEWART, a subject of the King of Great Britain, residing at Swampscott, in the county of Essex and State of Massachusetts, have invented certain new and useful Improvements in Machines for Operating on Soles; and I do hereby declare the following to be a full, clear, and exact description of the invention, such as will enable others skilled in the art to which it appertains to make and use the same.

The present invention relates to machines for shaping the soles of boots and shoes, and more particularly to machines of this type for molding a flat sole before it is incorporated in a boot or shoe.

It is desirable that the sole of a turned shoe shall be shaped to approximate the contour of the last bottom prior to the incorporation of the sole in the shoe. By shaping the sole in this manner, the operation of sewing the upper to the sole is facilitated, as the margins of the sole are located in close proximity to the bottom of the last owing to the curvature which has been imparted to the sole both transversely and in a lengthwise direction by the molding operation.

The object of the present invention is to provide a machine which is simple in construction, and which is operated with facility to mold a flat sole conveniently positioned therein.

With this object in view, a feature of the invention consists in the combination of co-operating sole molding forms, an arm supporting one of the forms, mechanism for oscillating the arm to traverse the form relative to the co-operating form, and mechanism for simultaneously rotating the form to cause each portion of the form to register with the corresponding portion of the co-operating form.

Further features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a side elevation of a

machine embodying the several features of the invention, and Fig. 2 represents a front elevation of the machine shown in Fig. 1 with the co-operating molds as shown in section.

In the present invention, the sole is conveniently positioned between co-operating sole molding forms and mechanism is provided for oscillating one of the forms in a lengthwise direction relative to the co-operating form and for simultaneously rotating the form to cause each portion of the form to register with the corresponding portion of the co-operating form. The sole is conveniently positioned upon a sole supporting form which is moved vertically by manually actuated means to position the sole in the path of movement of the sole molding form. The latter form is pivoted upon the lower end of an arm which is oscillated to cause the form to traverse in a lengthwise direction over the sole and apply the molding pressure progressively. During the oscillatory movement, the molding form is simultaneously rotated to cause each portion of the form to register with the corresponding portion of the sole supporting form. It will be obvious to those skilled in the art that with this construction and mode of operation a relative lengthwise movement is imparted to the two forms and corresponding portions of the forms are caused to register as the forms are moved relative to one another.

In the illustrated embodiment of the invention, a flat sole, indicated at 1, is positioned upon a sole supporting form 3 having a longitudinally curved face 4 provided with a recess 5, as shown clearly in Fig. 2. The sole is molded both transversely and in a lengthwise direction by a molding form 6 supported upon the lower end of an oscillatory arm, indicated generally at 7. The arm 7 is fulcrumed at its upper end upon a shaft 9, which is provided with a second arm 10 extending therefrom and conveniently operated through a connecting rod 12 and driving crank 13 secured to the main drive shaft 14 of the machine. As shown clearly in Fig. 2 of the drawings, the arm 7 is conveniently provided with side members 15 and 16 which form oppositely disposed upper and lower bearings for the shaft 9 and a shaft 17, to which the molding form 6 is

secured. In order to cause each portion of the molding form to register with corresponding portions of the supporting form as the molding form is traversed back and forth over the sole, the shaft 17 is provided with a toothed segment 20 secured to one end which engages with a curved rack 21 mounted upon an arm 22 which is secured to the machine frame. The rack 21 and the face 4 of the sole supporting form are both curved to conform with the arc of movement of the sole supporting form about the shaft 9, and it will be obvious to those skilled in the art that with this construction the molding form is traversed back and forth lengthwise of the sole, and is simultaneously rotated by the engagement of the intermeshing gears 20 and 21 to cause each portion of the molding form to register with the corresponding portion of the supporting form. In order to vary the extent of movement of the arm 7, and consequently the movement of the molding form, the arm 10 is adjustably connected with the connecting rod 12. To this end the arm 10 is provided with a curved slot 25 which receives a stud 26 supported in the end of the connecting rod 12, and clamped in any adjusted position in the slot through a clamping nut 27. The supporting form 3 is conveniently moved from a position convenient for the presentation of the sole thereon into a pressing position, and vice versa through the provision of treadle actuated mechanism which serves to raise and lower the form. To this end the form is supported upon a table 30 provided with a stem 31 which is vertically movable in guides formed in the machine frame. The stem 31 is provided with a rack 32 formed thereon and engaged by a gear segment 33 fulcrumed at 34 and provided with an operating arm 35. The operating arm is conveniently connected at its free end with a treadle rod 36. The table is normally maintained in a depressed position through the usual type of spring connection indicated at 37, which serves to normally elevate the treadle and connected mechanism. The sole supporting form is prevented from moving angularly with relation to the molding form through the provision of a stud 39 threadedly secured in the stem and received in a vertical guiding slot 40 formed in the machine frame, as shown clearly in the drawing. The sole supporting form is conveniently secured in place upon the table 30 through the provision of cooperating tongue and groove connections indicated at 41, and a spring pressed pin 42 supported in the table and arranged to have its end received in a corresponding recess 43 located in the

form when the form is positioned properly upon the table.

While it is preferred to employ the specific construction and arrangement of parts shown and described, it will be understood that this construction and arrangement is not essential, except so far as specified in the claims, and may be changed or modified without departing from the broader features of the invention.

The invention having been described, what is claimed is:

1. A sole molding machine having, in combination, coöperating sole molding forms, a pivoted arm supporting one of the forms, mechanism for oscillating the arm about the fulcrum to traverse the form in a curved path relative to the coöperating form, and mechanism for simultaneously rotating the form to cause each portion of the form to register with the corresponding portion of the coöperating form.

2. A sole molding machine having, in combination, a sole molding form, a pivoted arm supporting the form, mechanism for oscillating the arm about the fulcrum, a coöperating sole supporting form having a face curved to conform to the arc of movement of the molding form, and means for securing a relative movement of the two forms toward and from one another.

3. A sole molding machine having, in combination, a sole supporting form, a coöperating sole molding form, an oscillatory arm supporting the molding form, mechanism for oscillating the arm to move the form in a curved path, mechanism for simultaneously rotating the form, and manually actuated means for moving the sole supporting form toward and from the molding form.

4. A sole molding machine having, in combination, a sole molding form, an arm supporting the form, crank operated mechanism for oscillating the arm and form, connections including a curved rack and gear segment for simultaneously rotating the form, and a sole supporting form coöperating with the molding form, having a face conforming to the arc of oscillation of the sole molding form.

5. A sole molding machine, having, in combination, a sole supporting form, an oscillatory arm, a sole molding form pivoted upon the free end of the arm, mechanism for oscillating the arm to move the form in a curved path, and means for moving the sole supporting form toward and from the path of movement of the sole molding form.

WILLIAM C. STEWART.
